JOHN J. DOSSERT AND GEORGE L. STEWART, OF SYRACUSE, NEW YORK, ASSIGNEES TO CROUSE-HINDS COMPANY, OF SYRACUSE, NEW YORK, A CORPORATION OF NEW YORK.

PORCH-LIGHT.

1,235,665.

Specification of Letters Patent. Patented Aug. 7, 1917.

Application filed May 16, 1913. Serial No. 768,044.

To all whom it may concern:

Be it known that we, JOHN J. DOSSERT and GEORGE L. STEWART, of Syracuse, in the county of Onondaga and State of New York, have invented a certain new and useful Porch-Light, of which the following is a specification.

This invention has for its object the production of a porch light which in addition to lighting the porch also illuminates a sign or the street number of the building; and the invention consists in the combinations and constructions hereinafter set forth and claimed.

15 In describing this invention reference is had to the accompanying drawings in which like characters designate corresponding parts in all the views.

Figure 1 is a front elevation, partly in section of this porch light.

Fig. 2 is a sectional view on line "2—2," Fig. 1.

Fig. 3 is a sectional view on line "3—3," Fig. 1.

25 This porch light comprises, generally, a box or casing for the lamp, the box having means for connection with an electric conduit, and windows on two sides thereof which are penetrable by light.

30 As here shown the box is substantially rectangular in form and the front and under sides thereof are provided with transparent windows, the front wall being designed to contain the street number of the house or other building, and the wall of the lower side being designed to permit the rays of light to illuminate the steps and entrance of the residence, and in order to illuminate the steps most advantageously, the under 35 side is inclined upwardly and rearwardly as shown.

1 designates the casing which is here shown as formed with a nipple 2 at one end for connection with an electric conduit 3 in 45 closing service wires which are connected to the terminals of a lamp socket 4 supported by a suitable bracket 5 projecting inwardly from the rear wall 6 of the box. The nipple 2 is here shown as connected to the conduit 3 by means of a coupling 7 having a plug portion inserted in the nipple 2 and formed with an annular groove 8 in which the tapered fastening member 9 is tangentially

passed, the fastening member 9 being here shown as a screw threading transversely 55 through the nipple 2 and having a conical portion designed to bind in the groove 8 and hold the coupling in any angular position.

10 and 11 are respectively the window openings in the front and under sides of the 60 box, and 12 and 13 are panels secured in the openings, the panels being preferably glass.

As here shown the box is formed with a groove 14 extending around three sides of each opening 10 or 11 and open at the fourth 65 side of each opening for permitting the insertion of the panel of glass, the box being also formed with a face as 15 or 16 located at the fourth side of the opening 10 or 11, and flush with the rear side 17 of the groove 70 14 and against which face 15 or 16 one margin of the panel of glass rests when the remaining margins are in the groove 14 or 15.

Fastening means engage the exposed edge of each panel 12 or 13 and, as here shown, 75 the panel 13 arranged in the opening on the inclined side of the box, is held in position by fastening members as buttons 18, and the panel 12 on the front side of the box is held in position by an angular member 19 having 80 a flange for engaging the front face of the lower margin of the panel 12, the member 19 also engaging the exposed edge of said panel, both fastening members being secured to the box by any suitable means as screws 85 20 and 21, and the member 19 having open ended slots 22 for receiving the screws, the slots permitting removal of the member 19 when the screws are loosened.

In use, the box may be secured to a porch 90 or building in any suitable manner with the face in which the street number is set presented forwardly and the inclined face downwardly so that the number can be read from the street and the steps of the porch and the 95 entrance illuminated.

What we claim is:

An illuminating device comprising an elongated box oblong in general form in longitudinal section, the box having substantially flat sides and means at one end for connection to a conduit and also having at said end a support for a lamp socket, the support being located on the inner side of the wall at said end, the lower side of the 105 box being located on an incline relatively to

the front side and the rear side of the box, and said lower side and front side having transparent panels, substantially as and for the purpose described.

In testimony whereof, we have hereunto signed out names in the presence of two attesting witnesses, at Syracuse, the county of

Onondaga, in the State of New York, this 21st day of April 1913.

JOHN J. DOSSERT.
GEORGE L. STEWART.
